DESIGN FOR A LAMP SHADE

Harry M. Laxer, New York, N. Y., assignor to
Idealite, Inc., New York, N. Y., a corporation
of New Jersey

Application February 21, 1935, Serial No. 55,531

Term of patent 3½ years

To all whom it may concern:

Be it known that I, Harry M. Laxer, a citizen of the United States, and a resident of the city and State of New York, with a post-office address at No. 1140 Broadway, in the Borough of Manhattan, city and State of New York, have invented a new, original, and ornamental Design for Lamp Shades, of which the following is a specification, reference being had to the accompanying drawing, forming part thereof, in which—

Figure 1 is a perspective view of the lamp shade.

Figure 2 is a plan view looking down on the lamp shade.

Figure 3 is a plan view looking upward into the lamp shade.

I claim:

The ornamental design for a lamp shade, as shown.

HARRY M. LAXER.
